CLOTHES WRINGER

Thomas J. Little, Jr., Syracuse, N. Y., assignor to
Easy Washing Machine Corporation, Syracuse,
N. Y., a corporation of Delaware

Application July 26, 1937, Serial No. 155,664

9 Claims. (Cl. 68—263)

My invention relates to new and useful improvements in clothes wringers to be used preferably in connection with washing machines.

- An object of my invention is to provide a simplified wringer construction wherein means are provided for automatically latching the top bar or upper frame to the lower wringer frame during the operation of restoring pressure between the rolls.
- Another object of my invention is to provide, in a clothes wringer wherein the wringer rolls are normally spring held in pressure engagement, a top bar pivoted to the wringer assembly in such manner that the latch, which normally retains the spring in effective condition, is automatically engaged by the weight of the top bar, without exerting manual pressure on the top of the bar, during the operation of restoring pressure between the rolls.
- A further object of my invention is to provide, in a clothes wringer, means for readily varying the pressure between the rolls, said means being readily accessible for adjustment, and means for indicating the pressure between the rolls, said means being visible by the operator.

More specifically, my invention contemplates the provision, in a clothes wringer wherein a pair of rolls mounted in a wringer frame are normally held in pressure engagement by a spring and wherein a gear casing is mounted adjacent the rolls for housing mechanism for driving and reversing the rolls, of an upper frame element pivoted to the gear casing at its outer extremity at a point remote from the rolls so that during the operation of restoring pressure between the rolls the weight of the upper frame element causes automatic engagement of the latch between the lower frame element and the upper frame element, and further, the provision of a spring for aiding the effect of gravity on said upper frame element.

Other objects and advantages of my invention will be more apparent from the following description when taken in connection with the accompanying drawings, in which:

Figure 1 is a front elevation of a clothes wringer embodying the novel features of my invention and showing the clothes wringer mounted adjacent the side of the vat of a washing machine.

Figure 2 is a view taken on the line 2—2 of Figure 1.

Figure 3 is a view taken on the line 3—3 of Figure 2 showing the means for adjusting the spring pressure between the rolls.

Figure 4 is a view taken on the line 4—4 of

Figure 2 showing the means for adjusting the pressure between the rolls and showing the means by which the pressure between the rolls is indicated.

Figure 5 is a view taken on the line 5—5 of Figure 2.

Figure 6 is a view taken on the line 6—6 of Figure 2.

Figure 7 is a view taken on the line 7—7 of Figure 2.

Figure 8 is a view taken on the line 8—8 of Figure 7.

Figure 9 is a view similar to Figure 8 indicating the rolls in their dropped position.

Figure 10 is a view showing the latch between the major portion of the wringer frame and the wringer head or top bar of the frame.

Figure 11 is a view similar to that of Figure 1 showing the position of the top bar when pressure between the rolls has been released.

Figure 12 is a view similar to Figure 11 showing the wringer rolls in their dropped position with the top bar latched to the major portion of the wringer frame.

The clothes wringer of my invention, generally indicated by the numeral 11, is supported on a tubular housing 12 concentric with and through which the drive shaft 13 extends. The shaft 13 is preferably driven from the motor of the washing machine. The tubular housing 12 may be supported at its lower end and, in addition, be supported by a bracket 14 tied to the side walls 16 of the washing machine vat. A boss 17, integral with the wringer gear casing 18, has a bore for receiving the tubular housing and the lower end of the boss rests on a flange 19 formed near the top of the tubular housing 12. A hand-set plunger 21, registerable with any one of a series of apertures 22 formed in the upper end of the tubular housing 12, enables the wringer as a whole to be swung around the housing as an axis and set in any desired position as is common practice in the art. The shaft 13 extends into the gear casing and is suitably journaled therein.

The wringer gear casing 18, as shown in Figure 7, houses a pair of bevel gears 23 which are loose on the shaft 13. The bevel gears 23, as is common practice in the art, mesh with a bevel gear 24 which, through suitable connections presently described, drives the shaft 26 of the lower wringer roll 27. A reversing clutch 28, fixed but slidably along the shaft and suitably connected to a handle 29 by which it may be operated, enables either of the bevel gears 23 to be

driven from the shaft 13 to cause the roll 27 to be driven in one direction or the other. The bevel gear 24 is integrally connected to one part 31 of a coupling member. The other part 32 of the 5 coupling member has a U-shaped slot in the end thereof through which a pin 33, connected to the coupling part 31, extends. The coupling part 32 lies loosely in the coupling part 31 so as to permit some movement of the coupling 10 part 32 with respect to the part 31. The end of the shaft 26 has a pin 34. The end of the coupling part 32 has a slot into which the pin 34 loosely fits. A driving connection is thus provided between the shaft 13 and the shaft 26 15 of the roll 27.

A bearing 36 for the shaft 26 is pivoted at 37 in the wringer frame 38 which supports the wringer rolls. The opposite end of the shaft 26 is supported in a bearing 39 mounted on a plate 41 extending between the sides of the wringer frame 38. One pair of links 42 of a toggle is connected at 43 to the plate 41 and, at 44, to the other links 46 of the toggle. A shaft 47 is rigidly connected to the links 46 by flattening one side 25 of the shaft 47 and conforming the opening through the links 46 to the shape of the shaft, as indicated at 48. The links 42 are connected together by a cross part 49, and the links 46 are connected together by a cross part 51. A ledge 30 52 is formed on the cross part 49 so that the cross parts will engage each other and limit the movement of the toggle in one direction. The outer end of the shaft 47 extends through the wringer frame and is provided with a handle 53 35 by which the shaft 47 may be rotated to make or break the toggle 42, 46.

The upper roll 54 is driven from the lower roll by the pressure between them and the shaft 56 of the upper roll is supported in bearing blocks 57 and 58. The bearing blocks 57 and 58 are freely slideable in guides 59 mounted in the wringer frame 38. A pair of slotted links 60 are pivoted to the guides and a pin 61, extending through the bearing block 58, registers in the slots. The upward movement of the bearing block is thus limited by the links 60. A bow-shaped spring 63 bears on the top of the bearing blocks, as indicated at 64, and normally holds the rolls in pressure engagement.

50 As shown in Figures 3 and 4, the spring 63 has a threaded opening 66 at its center into which is threaded an adjustment screw 67. The end of the adjustment screw has a pin 68 which engages a bracket 69 supported from the under 55 side of the upper wall of the top bar 71 of the wringer frame. The end of the adjustment screw 67 is rectangular and is fitted in a rectangular opening 72 formed in a finger wheel 73. A slot 74 is provided in the top bar 71 through which 60 a portion of the circumference of the finger wheel 73 extends, as indicated at 76. An arm 77, pivoted at 78 to the top bar 71 of the wringer frame, has one end provided with a bent forked portion 79 which straddles the spring 63, as shown 65 in Figure 3 at 81. Beyond the pivot 78, the arm 77 extends upward at an angle and is provided at its end with indicia 82—"low," "medium" and "high"—which indicate low spring pressure, medium spring pressure and high spring pressure. 70 The top bar 71 is provided with an opening 83 through which the indicia on the end of the arm 77 may be viewed.

It will now be appreciated that upon rotating the finger wheel 73, the adjustment screw may be threaded into or out of the threaded opening

in the spring 63 to adjust the pressure of the spring. By reason of the pivotal connection of the arm 77 to the top bar 71, the outer end of the arm will move in accordance with the spring pressure so that the tension of the spring, whether high, medium or low, will register in the opening 83, as indicated in Figure 1.

The top bar 71 of the wringer frame, as shown in Figures 1 and 2, is pivoted on a pair of lugs 84 at the extreme outer end of the gear casing 18 by means of pivot pins 86. The top bar is U-shaped in cross section, extends across the top of the gear casing 18 and the major portion 38 of the wringer frame, and is of sufficient width and length so as to fit down over the top of the gear casing 18 and the wringer frame portion 38. At its opposite end, the top bar is provided with a latch opening 87. Below the opening 87 the metal of the top bar is bent outward to form a cam surface 88 on the inside of the top bar.

A latch, generally indicated by the numeral 89, more clearly shown in Figure 10, comprises a stop piece 91, a pivot pin 92 for the stop piece, a latch arm 93 and a latch cam 94. A spring 96, extending around the pivot pin 92, having one end bearing against the stop piece 91 and the other end bearing against the wringer frame 38, normally urges the latch arm 93 in a counter-clockwise direction, as viewed in Figure 10. The latch cam 94 has a cam surface 97 and a cam surface 98. The latch arm extends above the latch cam 94 and has a portion 99 bent at right angles to the arm and an upwardly extending portion 101. When the top bar 71 is down in position and pressure is on the rolls, the latch cam 94 lies in the opening 87 in the top bar. 20 25 30 35

Means are provided for releasing the latch to enable the top bar of the wringer frame to move upward around its pivot 86. As shown in Figures 1, 2, 5 and 6, the release means comprises a 40 pair of release bars 102, one on each side of the top bar, so that pressure between the rolls may be released from either side of the wringer. Since each of the release bars 102 and its associated mechanism is the same, a description of one will suffice. 45

The release bar 102 has an inwardly extending portion 103 which, as shown in Figure 5, is supported on a pivot pin 104 mounted on a bracket 106 rigidly supported from the top bar 71. A 50 trip arm 107 is pivoted at 104 to the bracket 106 and is pivoted at 108 to the release bar 102. An inwardly extending part 109 of the trip arm 107 engages the lower edge of a latch keeper 111. The opposite end of the release bar 102 is provided with an inwardly extending portion 112 which houses a pin 113 which extends through the wall of the top bar 71. The inner end of the pin has a pin and washer assembly 114 by which the pin 113 is retained in position. The end of 60 the pin has a head 116 for forming a backing for a spring 117 which normally presses on the release bar so as to retain the release bar in the position shown in Figure 6. Upon depressing the release bar 102 against the action of the spring 117, the end 109 of the trip arm 107 is moved upward around its pivot 104 to move the latch keeper 111 upward, as indicated in dotted lines in Figure 5. The two arms of the latch keeper 111 extend across the top of the wringer rolls at 70 the sides thereof and the ends thereof are pivoted at 120 to the side walls of the top bar. The opposite ends of the arms are joined together by a cross bar 121. The cross bar has a forwardly extending lug 122 which, as shown in 75

Figure 7, normally lies on top of the bent portion 99 of the latch arm 93 and retains the latch in the position shown in Figure 7.

When the rolls are in the position shown in Figure 7 and the operator is wringing clothes, if she catches her fingers between the rolls or if a large bunch of clothes causes the rolls to stall, pressure between the rolls may be instantly released by pressing on either of the release bars 102. Pressure on the release bar 102 raises the end of the trip arm 107 into engagement with the latch keeper 111 so that the lug 122 on the end of the latch keeper 111 is raised upward out of engagement with the end 101 of latch arm 93. The full pressure of the spring 63 is then placed upon the latch cam 94 so that the latch is cammed in a clockwise direction, as viewed in Figure 7, and the top bar of the wringer frame flies upward. As soon as the top bar is in its upper position, as shown in Figure 11, the upper roll is free to raise upward and there is no pressure between the rolls. As soon as the latch cam 94 is out of the opening 87, the spring 96 moves the latch arm 93 to the position shown in Figure 10. When the operator desires to restore the pressure between the rolls, she moves the handle 53 from the position shown in Figure 7 to that shown in Figure 12. This breaks the toggle 42, 46 and moves the lower roll down from its normal position to the position shown in Figure 9. When the lower roll is lowered, the upper roll follows it and moves to the position shown in Figure 9, whereupon the top bar is free to move downward under the action of gravity around the pivot point 86 as a center.

The weight of the upper frame or top bar is such that when it moves down, the latch 89 is cammed aside until the opening 87 registers with the cam 94, whereupon the cam snaps into position in the opening under the action of the spring 96. During the initial downward movement of the top bar 71, the latch keeper 111 will be maintained in its lowermost position with respect to the top bar against the trip arm 107 until lug 122 of the keeper is engaged by the latch arm extension 101. The outer end of the latch keeper is then supported by the latch 89 until the latch cam enters opening 87, whereupon the latch extension passes outwardly beyond the lug 122 out of supporting engagement therewith. As the cam 94 enters opening 87 the latch keeper will be maintained by the latch 89 in a raised position so that when released by the latch 89 the latch keeper 111 falls down so as to lie in the position shown in Figure 7 to retain the latch in latched condition.

It will, of course, be appreciated that considerable force is required to cause the latch cam 94 to engage in the opening 87. This force is supplied by the weight of the wringer head or top bar 71, the effect of which is appreciably increased by pivoting it at the extreme end of the gear casing 18, as shown in the drawings. Moreover, in order to reduce the weight of the wringer head or top bar 71 required to cause the latch to engage in the opening 87, I have found it desirable to secure a spring 123 between the wringer head and the top of the gear casing, as indicated at 124 and 125. Of course, the effect of the spring is increased the further from the pivot 86 that it is placed, but the location for the spring 116 shown in Figure 7 is convenient since it may be easily mounted in this position and a heavy spring is not required to cause automatic latching. This eliminates the necessity of

the operator pressing on top of the top bar in order to latch the top bar to the wringer frame portion 38. After the top bar is latched in position, the handle 53 is moved from the position shown in Figure 12 to that shown in Figure 7. The toggle 42, 46, during this movement of the hand lever 53, is brought from the position shown in Figure 9 to that shown in Figure 8 where it is past dead center and locked in position by the engagement of the parts 49 and 51. This movement of the toggle raises the outer end of the roll 27 carrying upward with it the upper roll 54 so that the rolls are brought to the position shown in Figure 7, in which position the rolls are under the full compression of the spring 63.

It will be appreciated that I have provided a simple means of adjusting and indicating the pressure between the rolls and have provided a simple means for causing the wringer head to be brought into operative latching engagement with the wringer frame so that pressure may be applied between the rolls. It will further be apparent that various modifications may be made in the form and relation of the parts without departing from the spirit of my invention as set forth in the appended claims.

I claim:

1. In a clothes wringer of the type wherein a pair of wringer rolls mounted in a wringer frame are normally held in pressure engagement by a spring and wherein a gear casing mounted adjacent the wringer frame houses mechanism for driving and reversing the rolls, a top bar pivoted to said gear casing at its extreme outer end away from the rolls, a latch connected between said wringer frame and said top bar at the opposite end of said wringer head, means for releasing said latch to enable said top bar to move upward about its pivot and to enable separation of the rolls, means for lowering and raising said rolls to first allow the weight of the top bar to be effective by virtue of its pivotal connection to cause automatic reengagement of said latch and subsequently restore the pressure between the rolls.

2. In a clothes wringer of the type wherein a pair of wringer rolls mounted in a wringer frame are normally held in pressure engagement by a spring and wherein a gear casing mounted adjacent the wringer frame houses mechanism for driving and reversing the rolls, a top bar pivoted to said gear casing at its extreme outer end away from the rolls, a latch connected between said wringer frame and said top bar at the opposite end of said top bar, means for releasing said latch to enable said top bar to move upward about its pivot and to enable separation of the rolls, means for lowering said rolls to enable the weight of the top bar to be effective by virtue of its pivotal connection to cause automatic reengagement of said latch, a spring connected between said frame and top bar for aiding the latching movement of the top bar, said means being capable of raising said rolls against the pressure of said spring to restore the pressure between the rolls, and additional means for maintaining said last mentioned means in pressure applying relation with said rolls.

3. In a clothes wringer having a frame provided with a movable top bar, a pair of rolls mounted in said frame at least one of which is movable toward and from the other, a spring for maintaining said rolls in pressure engagement, means including a latch for releasably maintain-

ing the top bar in fixed relation to the frame and rendering said spring effective, means for releasing said latch to permit said top bar to move upward and allow the separation of the rolls, 5 means rendered effective by the weight of the top bar during the downward movement thereof to cause automatic engagement of the latch and for actuating the rolls with respect to the spring for restoring pressure between the rolls without 10 exerting manual pressure on top of the top bar, and a spring connected between said top bar and frame for aiding the latching movement of the top bar.

4. In a clothes wringer, a pair of rolls at least 15 one of which is movable toward and from the other, a spring for maintaining said rolls in pressure engagement, a wringer frame having upper and lower portions, a latch between said frame portions, said upper portion being pivoted 20 at one side of the wringer, means for releasing said latch to permit said upper frame portion to move upward and enable separation of the rolls, means for enabling the weight of the upper frame portion to cause automatic engagement of 25 the latch during the operation of restoring pressure between the rolls without exerting manual pressure on the upper frame portion, and a spring connected between said upper and lower frame portions for aiding the latching movement 30 of the wringer head.

5. In a clothes wringer, a pair of rolls at least one of which is movable toward and from the other, supporting means for said rolls including two frame elements mounted to have relative 35 movement toward and from each other, a spring carried by one of said frame elements and operatively connected with a roll for maintaining said rolls in pressure engagement, fastening means connected with one of the frame elements 40 and releasably engageable with the other frame element for holding said frame elements against said relative movement and rendering the spring effective, means for actuating the fastening means to release the frame elements from each 45 other and to render the spring ineffective for maintaining the rolls in pressure engagement, manually operated means connected with the support for producing movement of the rolls in one direction relative to the frame elements and 50 to said spring to allow free relative movement of the frame elements and cause engagement of the fastening means while maintaining the spring ineffective, said manually operated means being capable of producing movement of the rolls in 55 the opposite direction relative to the frame elements and spring to bring said rolls in pressure engagement with each other.

6. In a clothes wringer, a pair of rolls at least one of which is movable toward and from the other, a support for said rolls including upper and lower frames pivotally connected together, a spring carried by said upper frame for maintaining said rolls in pressure engagement, means including a latch for releasably holding the frames

against relative pivotal movement and rendering said spring effective, means for releasing said latch to permit said upper frame to move upward and enable the separation of the rolls, and means for producing movement of the rolls with 5 respect to the lower frame away from and toward the upper frame for enabling the weight of the upper frame to cause automatic engagement of the latch during the operation of restoring pressure between the rolls without exerting 10 manual pressure on the top of the upper frame.

7. In a clothes wringer, a pair of rolls at least one of which is movable toward and from the other, a spring for maintaining said rolls in pressure engagement, a lower wringer frame, an upper wringer frame and a latch between said frames, said upper wringer frame being pivoted at one side of the wringer, means for releasing said latch to permit said upper wringer frame to move upward and enable separation of the rolls, and 20 means for producing movement of the rolls with respect to the lower frame away from and toward the upper frame for enabling the weight of the upper frame to cause automatic engagement of the latch during the operation of restoring 25 pressure between the rolls without exerting manual pressure on the wringer head.

8. In a clothes wringer wherein a pair of wringer rolls mounted in a frame are normally held in pressure engagement by a spring, a top 30 bar pivoted to the wringer frame and a latch between said wringer frame and said top bar, means for releasing said latch to allow pivotal movement of the top bar and separation of the rolls, means for lowering said rolls to enable the 35 weight of the top bar to be effective by virtue of its pivotal connection to cause automatic reengagement of said latch, said latter means being capable of raising said rolls against the pressure of said spring to restore the pressure between the rolls, and additional means for maintaining said last mentioned means in pressure applying engagement with said rolls in said 40 raised position.

9. In a clothes wringer wherein a pair of 45 wringer rolls mounted in a support are normally held in pressure engagement by a spring, said support comprising upper and lower frames pivoted together, a latch between said wringer frames, means for releasing said latch to enable 50 separation of the rolls, means for lowering said rolls to enable the weight of the upper frame to be effective by virtue of its pivotal connection to cause automatic reengagement of said latch, a spring connected between said upper and lower 55 frames for aiding the latching movement of the upper frame, said means being capable of raising said rolls against the pressure of said first spring to restore the pressure between the rolls, and additional means for maintaining said last 60 mentioned means in pressure applying engagement with said rolls.

THOMAS J. LITTLE, JR.
